UNITED STATES PATENT OFFICE.

CHARLES E. REED, OF BARTOW, FLORIDA.

WATER-HEATER.

1,156,814.

Specification of Letters Patent. Patented Oct. 12, 1915.

Application filed February 24, 1915. Serial No. 10,291.

To all whom it may concern:

Be it known that I, CHARLES E. REED, a citizen of the United States, residing at Bartow, in the county of Polk and State of Florida, have invented certain new and useful Improvements in Water-Heaters; and I do hereby declare the following to be a full, clear, and exact description of the invention, such as will enable others skilled in the art to which it appertains to make and use the same.

This invention relates to water heaters, and more especially to those including a stand boiler within a casing; and the object 15 of the same is to provide means for heating the water in such a boiler by a fluid fuel burner which is bodily insertible in or removable from the lower portion of the casing or jacket, which latter therefore becomes a flue carrying the products of combustion upward around the boiler to an outlet.

A further object of the invention is to improve the means for supporting the heater 25 so that as a unit it may be bodily withdrawn for cleaning, repairing or filling its tank.

A still further object of the invention is to improve the structure of the stand on which the device is mounted.

30 The following specification sets forth the preferred manner of carrying out my invention, reference being had to the accompanying drawings wherein—

Figure 1 is a central vertical sectional view of this heater complete. Fig. 2 is a perspective detail of the shelf and slide on an enlarged scale. Fig. 3 is a similar enlarged sectional detail of the stand, and Fig. 4 a still further enlarged detail showing the 40 manner of connecting the jacket with the stand.

The stand boiler B illustrated in the drawing is that now in general use and by preference I employ one measuring 36 45 inches in length and about 10 inches in diameter, and the inlet and outlet pipes I and O are those usually employed. It is quite possible that the inlet pipe, instead of taking its water from the house system direct, may 50 have taken it from the coil within the furnace or the water-back within the range, and in either case the water flowing in at the point I will be warm or hot if there is fire in the furnace or range. If such is the manner 55 in which the boiler is connected up, then my improved water heater finds its greatest

utility at times when the furnace, for instance, is not running, and there is a call for hot water in the house system. The latter will be connected with the outlet pipe O. 60 But ordinarily this device is employed where there is no furnace, and cold water is admitted at I and heated by the means described below, so that warm or hot water is drawn out at O and carried to the point of 65 use. Besides inlet and outlet pipes, there is a mid-length pipe M leading from a point at about the center of the height of the boiler to a point E where it enters its lower end, and this pipe may have its own faucet 70 F. This supplemental pipe is also often employed where the boiler is connected with the furnace, and I lay no claim of novelty thereto.

Coming now to the details of the present 75 invention, I inclose the boiler B within an upright cylindrical jacket 1 which surrounds it and is connected with it by brackets 2 or any suitable devices holding the walls of these elements slightly spaced so as to 80 produce an annular flue or jacket space around the boiler, and the upper end of the casing or jacket extends above the top of the boiler and is shaped into an outlet 3 from which the products of combustion may escape in any suitable manner. The lower end of the jacket depends to a considerable distance beneath the bottom of the boiler, has an opening 4 in its front side, and rests at 85 its lower edge upon a stand best seen in 90 Figs. 3 and 4. This stand comprises a ring 5 pierced with about three holes 6 and with two diametrically opposite eyes 7. Into said holes are screwed the upper ends of legs 8 which are preferably of pipe having rather 95 long threads for purposes of adjustment, and lock nuts 9 upon the threads as best seen in Fig. 1. The lower end of each leg may have a foot 10 secured by a screw 11 or otherwise to the floor. Riveted within the 100 jacket at points quartering to its front opening 4 are two L-armed brackets 12 which stand above the eyes 7, and small bolts 13 pass down through these brackets and through said eyes with their nuts 14 below 105 the ring 5, so that by tightening up said nuts the jacket is drawn firmly down onto the ring of the stand. The latter is adjusted by means of its legs to hold the entire jacket strictly vertical and steady.

110 The heating unit of itself may be any which will operate successfully in conjunc-

tion with the boiler and its jacket, but preferably it will employ a burner 20 for fluid fuel. While said fuel might be gas led to the burner through a pipe or hose so that the 5 user could employ natural or artificial gas if desired, in many sections of the country the fluid fuel will be oil and the burner must be of a type which will vaporize and burn such oil. In other sections of the country 10 the fuel will be kerosene which is always readily obtainable and cheap, and I will illustrate and describe the heater as of this type. From the burner 20 leads a pipe 21 to a casing 22, here shown as having legs 15 23 rising from a sheet metal slide 24, and within said casing is rotatably mounted a tank 25 having a knob or handle 26 on one end of its axis so that the tank can be turned and the liquid will flow into the casing 22, and thence along pipe 21 to the burner 20. Secured to and rising from the 20 slide at a point about midway between the tank and burner is an upright sheet-metal shield 27 pierced with a hole 28 for the passage of the pipe 21, and this shield is of a size and shape to close the opening 4 when the slide stands in such position that the burner is centered within the lower end of the jacket. The midlength or system of 25 pipes M I now preferably provide with a coil 29 disposed beneath the boiler and directly above the burner, and therefore the flames rising from the burner heat this coil and the water within it, then heat the bottom 30 of the boiler, and finally flow upward through the jacket space and heat the sides of the boiler. It will hardly be necessary to amplify the illustration to show that the pipe 21 might be a hose connected directly 35 with the natural or artificial gas system if the dwelling be so provided, but even in that event I would have the slide movable as will be next described.

Extending through the bottom of the 40 opening 4 in the jacket and over the ring 5 to its rear side as indicated in dotted lines in Fig. 3 is a sheet-metal shelf 30 having its side edges beaded or turned upward and inward into guides 31 as best seen in Fig. 4. This shelf is as wide as the opening 4 but of less width than the internal diameter of the jacket, and its length is such that it extends through the opening and beyond the jacket about as far on the outside as 45 it does on the inside. The sheet-metal slide 24 has its side edges turned downward and then outward into flanges 32 which are adapted to slide under the guides 31, and the front end of the slide is curled downward 50 into a handle 33. All of the parts are of course of metal.

With the above construction and after the device has been set up, we may assume that the part stand as seen in Fig. 1. The operator now grasps the handle 33 and draws

the slide outward on shelf 30 so that the shield 27 comes out of the opening 4 and the burner 20 follows it through said opening, at least to a position where it can be lighted. If the supply be a rotary tank as shown at 50 25, it is controlled by means of the knob 26. If the fuel is gas led through a flexible pipe 21, it will be controlled by the usual cock. In any event the fuel is permitted to flow to the burner and a match is applied, 55 and then the entire heater is moved by shoving the slide 24 inward so that its flanges 32 move under the guides 31, and its burner 20 comes to rest directly beneath the coil 29 at the time that its shield 27 closes the opening 4 in the jacket 1. Air is now admitted 60 through the ring 5 of the stand on either side of the shelf to supply combustion to the burner, and the flames rising therefrom heat the coil and the boiler as above explained. 65 By actual tests from a working machine I have found that I can raise the temperature of the water thirty degrees in thirty minutes, and the operating cost with kerosene at fifteen cents a gallon is about one and one half cents an hour. Manifestly the cost 70 would differ with other kinds of fuel, or it would be much less if the heater were employed to raise the temperature of water which was already warm when it was fed in 75 at the point 1. In other words, it often occurs that the heating system connected with the furnace or range is not such as will more than warm the water in the stand boiler, and for laundry and other purposes a supplemental heater is desirable unless one be willing to considerably increase the heat in the 80 regular system. As above stated, this device can be used when there is no fire in the house, or it could be installed where the boiler has 85 no connection with the furnace or range. At P in Fig. 1 is shown a peep hole through the jacket 1, which may well be covered with mica held within a removable frame or otherwise, and through the same the flame 90 can be seen at any time.

What I claim is:

1. In a water heater, the combination with a stand boiler and its inlet and outlet pipes, a jacket inclosing the boiler and constituting a flue, the jacket extending beneath the lower end of the boiler and having an opening in its front side, and a supporting stand for the jacket; of a shelf extending through said opening inside and outside the jacket 115 and having guides along its edges, a slide having flanged edges movably mounted in said guides and a handle at its front end, a heating element mounted on said slide and including a burner at its inner end, and a shield rising from the slide forward of the burner and adapted to close said opening. 120

2. In a water heater, the combination with a stand boiler and its inlet and outlet pipes, a jacket inclosing the boiler and constituting 125

- ing a flue, the jacket extending beneath the lower end of the boiler and having an opening in its front side, and a supporting stand for the jacket; of a shelf extending through 5 said opening inside and outside of the jacket and having guides along its edges, a slide above the shelf having its edges movably mounted in said slides, a shield rising from the mid-length of the slide and adapted to 10 close said opening in the jacket, the shield having a hole, and a heater including a burner mounted on the slide at one side of said shield, a tank mounted thereon at the other side, and a pipe connecting these elements and passing through said hole.
3. In a water heater, the combination with a stand boiler having inlet and outlet pipes, a pipe connecting its mid-length with its lower end and having a coil standing beneath said end, and a jacket surrounding the boiler and constituting a flue, the jacket depending below the boiler and having a hole in its front; of a shelf leading through 20 said hole, a slide movably mounted on the shelf, a shield rising from its mid-length
- and adapted to close the hole, and a heater comprising a burner on the inner end of the shelf adapted to stand under the coil when the shield closes said hole, a tank on the outer end of the shelf, and connections between the burner and the tank. 30
4. In a water heater, the combination with a stand boiler, an upright cylindrical casing inclosing the boiler and extending above and below it, brackets spacing these elements to produce an annular space around the boiler, the casing having a hole in its front below said boiler, and a heating unit adapted for insertion and removal through said hole; of a stand comprising a ring beneath the lower end of the casing, longitudinally adjustable legs supporting said ring, angle brackets within the casing, and bolts connecting said brackets with the ring. 35
- 40
- 45

In testimony whereof I affix my signature in presence of two witnesses.

CHARLES E. REED.
